CLAIM

The ornamental design for a chicken ornament, as shown and described.

DESCRIPTION

FIG. 1 is a rear, right, top perspective view of a chicken ornament, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

There is no claim to color or shade.

There is no claim to contrasting color or contrasting shade. The broken line defines the bounds of the claimed design and forms no part thereof. The lightened portion of the chicken ornament forms no part of the claimed design.

1 Claim, 7 Drawing Sheets
